CLAIM

The ornamental design for a physiological monitor, as shown and described.

DESCRIPTION

FIG. 1 is a front- perspective view of a physiological monitor showing our new design;

FIG. 2 is a left view thereof;

FIG. 3 is a right view thereof;

FIG. 4 is a front view thereof;

FIG. 5 is a rear view thereof;

FIG. 6 is a bottom view thereof; and,

FIG. 7 is a top view thereof.

The broken lines depict portions of the physiological monitor that form no part of the claimed design; the broken lines form no part of the claimed design.

1 Claim, 3 Drawing Sheets(56)
